UNITED STATES PATENT OFFICE.

CHAUNCY A. SAGER, OF ELMONTE, CALIFORNIA, ASSIGNOR TO JAMES T. POLLOCK, OF LOS ANGELES, CALIFORNIA.

THILL-COUPING.

SPECIFICATION forming part of Letters Patent No. 758,193, dated April 26, 1904.

Application filed April 7, 1902. Renewed March 8, 1904. Serial No. 197,177. (No model.)

To all whom it may concern:

Be it known that I, CHAUNCY A. SAGER, a citizen of the United States, residing at Elmonte, in the county of Los Angeles and State 5 of California, have invented new and useful Improvements in Thill-Couplings, of which the following is a specification.

My invention has for its objects the ready coupling and uncoupling of the shafts or 10 tongue from the axle and the prevention of noise of the thill in the coupling when in use.

My invention is described herein and is illustrated in the accompanying drawings, forming a part thereof, in which—

15 Figure 1 is a perspective view of the fragment of a thill and an axle with my coupling applied to couple them together. Figs. 2 and 3 are side views of the same with the axle removed, cut on the vertical plane on lines 2 and 20 3, respectively, of Fig. 1 looking in the direction indicated by the arrow.

25 In the drawings, A is the axle, to which the thill-coupling is mounted in the usual manner. The thill-coupling is composed of the clip B, which surrounds the axle, which clip has the 30 forwardly and downwardly projecting arms B', having an upwardly-opening notch B'', the lower portion of which projects toward the front of the arm for the reception therein of the ends of the bolt, which passes through the 35 thill-iron D and remains therein when the thill is removed from the coupling-iron. This bolt is a smooth piece of iron without a head, so that it may be easily removed from the thill-iron in case it is desired to use the thill in a 40 buggy not provided with my improved thill-coupling. In the lower part of the arm B' is 45 rotatively mounted a rod E, the ends of which project beyond the arms, on which ends are 50 rigidly mounted stop-plates F to prevent the longitudinal movement of bolt C when the thill is coupled to the axle, which are attached to catches H, also rigidly affixed to rod E, which catches prevent bolt C from becoming 55 accidentally displaced from the notches. The stop-plate and catch may be cast integral, if desired. The backward movement of these 60 stop-plates is prevented by lugs B''', which 65 keep the catches from contacting with bolt C.

On rod E between the arms B' is rigidly attached a spring G, the free end of which bears firmly against the ends of the thill-iron and keeps it and bolt C from having any vibratory movement, thereby avoiding the rattling noise incident to the use of the thill when coupled 55 in an ordinary coupling without any antirattling device. In removing the thill from the coupling it is unnecessary to use a wrench to remove the thill, as by pressing the spring toward the clip and the catch away therefrom 60 the thill may be raised to carry the bolt C out of the notch. If the bolt C is firmly fixed in the thill-iron, the stop-plates may be omitted.

Having described my invention, what I claim as new, and desire to secure by Letters 65 Patent, is—

1. A thill-coupling composed of a clip having forwardly and downwardly projecting arms, said arms having in the upper portion thereof an upwardly-opening recess therein 70 adapted for the entry and retention of a bolt; a rod extending through the lower portion of the said arms; a spring rigidly affixed to said rod and extending upwardly and adapted to bear against the end of the thill-iron when in 75 said coupling; catches on the ends of said rod exterior the said arms extending upwardly and adapted to prevent any longitudinal movement of a bolt in the recesses in said arms.

2. A thill-coupling composed of a clip having forwardly and downwardly projecting arms, said arms having a notch in the top thereof; a rod mounted in the downwardly-projecting portion of said arms; a stop-plate and catch affixed to said rod exterior the said arms; 85 a spring affixed to said rod between said arms and adapted to bear against the thill-iron when in place in the coupling in combination with a thill having a bolt in the iron thereof adapted to slip into the notches of the arms of 90 the clip.

In witness that I claim the foregoing I have hereunto subscribed my name this 1st day of April, 1902.

CHAUNCY A. SAGER.
